TELEPHONE SUPPORT

Alexander G. Harris, Bloomfield, N. J.

Application October 3, 1946, Serial No. 701,020

3 Claims. (Cl. 179—157)

1

This invention relates to improvements in telephone supports.

In using telephones, especially for frequent use and for conversations of long duration, the holding of the phone manually becomes a tedious act, and decreases one's efficiency.

It is the object of this invention to provide a telephone support dispensing with the need for manually supporting the phone, the support automatically supporting the phone in convenient position.

A further object of the invention is to provide a device of the character described which may be conveniently secured to and removed from a telephone, which may be economically manufactured, and which is practically indestructible in use.

Embodiments of structures employing my invention are shown in the accompanying drawings and described in detail in the ensuing specification. Such embodiments are merely by way of example; the invention is not limited thereto but includes all other forms which would come within the scope of the appended claims. In the drawings,

Fig. 1 is a top plan view of a telephone support embodying the invention.

Fig. 2 is a side elevational view thereof, taken on line 2—2 of Fig. 1.

Fig. 3 is a perspective view illustrating the position in which the device of my invention is secured to a telephone, the latter being shown fragmentarily and in dotted lines.

Fig. 4 is a perspective view of a modification of the invention,

Fig. 5 is a side elevational view of another modified form of the invention.

Fig. 6 is a fragmentary, medial vertical sectional view thereof.

Fig. 7 is a transverse sectional view, taken on line 7—7 of Fig. 5.

Fig. 8 is a fragmentary, elevational view of another modification of the invention, and

Fig. 9 is a perspective view of the arm segment adapted to be used in connection with the said modification.

As shown in the drawings, the telephone support of my invention comprises a member 10 of generally flat form and of ovate external outline having opposed spaced arms 11 and 12 which define therebetween an ovate recess 13 which is partly closed by the inturned free ends 14 and 15 of said arms. The ovate recess is preferably provided with a resilient lining 16 of rubber or similar material. The support 10 is provided, at the end thereof remote from the ends

of the arms, with a depending stud 17, preferably secured thereto at right angles to the general longitudinal axis or plane of the support 10, and preferably of generally triangular outline.

In the drawing, a single anchoring depending stud 17 is shown; however, if desired, a plurality of such studs may be provided, either in the form of separate units or in the form of a continuous extension of stud 17.

In the forms of invention shown in Figs. 4—8 the end of one of the arms of the support 10 comprises an arm segment yieldably secured thereto by spring means in such manner that the segment is normally spring urged into position to constitute the inturned end of said arm to cooperate with the inturned end of the other arm in holding the support 10 on the phone as shown in Fig. 3. The segment and arm are provided with complementary interengaging means to assure proper registration of said parts. The segment may be readily manually displaced against the tension of the spring means for facility in initially snapping the holder over the neck N of the phone or in removing the same therefrom. When the segment is displaced against the tension of the spring means, the arm to which the segment is secured has no inturned end. Thus the recess 13 is widened and the holder may be readily snapped over the neck N of the phone, the segment then moving into normal position to constitute the inturned end of said arm and to latch the holder onto the phone, responsive to the spring tension.

In the form shown in Fig. 4, the segment 18 is provided with an elongated finger 19 and is pivoted as at 20 to the bifurcated extension 21 of the arm 12. The spring 22 bears against the end of the elongated finger 19 to pivotally urge the segment 18 into the position in which the same defines the inturned end of the arm 18. The free end of finger 19 engages the lining 16 or other stop means to assure registration of segment 18 in position to normally define the inturned end of the arm.

In the form shown in Fig. 5, the segment 23 is slidably arranged in a recess 24 in the arm 12, and is provided with a stem 25 through which the pin 26 passes. Spring 28, positioned within the arm 12, bears against the end of the stem 25 to normally urge the segment 23 into position to define the inturned end of the arm 12. Pin 26 is received within slots 27 in the arm 12 to assure registration of segment 23 in position to normally define the inturned end of the arm.

In the form of invention shown in Figs. 8 and 9,

one of the arms—for example, the arm 12' of the support 10, is preferably shortened and is completed by yieldably securing an arm segment 29 thereto by means of a spring 30, the opposite ends of the latter being fixed to the shortened arm and segment by any desired or convenient securing means 31, 32. The shortened arm 12' and the arm segment 29 are preferably provided with complementary interengaging registering means, such as recess 33 and the boss 34, whereby the arm segment 29 will normally complement the shortened arm 12' to complete the same and constitute the end thereof.

The spring 30 is preferably provided with side flanges 35 and with a slotted or otherwise weakened portion 36 to facilitate bending the spring medially to permit moving the segment 29 downwardly as indicated in dotted lines in Fig. 8 for facility of application of the support to a phone P.

The support 10 is secured to the phone by inserting the neck N of the latter into the ovate recess 13, preferably at a point adjacent the receiver end of the phone, as shown in dotted lines in Fig. 3; then by sliding the support slightly along the neck N, toward the transmitter end of the phone, the support 10 is locked on the increasingly larger cross-section of the neck N of the phone. The resilient lining 16 in the ovate recess further assists the wedging action.

With the support 10 positioned on the phone, the latter may be conveniently suspended from the user's shoulder, the support 10 being generally in a horizontal position and the depending stud 17 providing an anchoring grip or non-slide means which will prevent accidental displacement of the device.

The device may be made from any suitable material; it will be apparent from a consideration of the foregoing description, and an examination of the drawings, that it may be conveniently molded of plastic materials.

While I have shown in the drawings and described in the above specification, convenient forms of structures embodying my invention, it will be apparent from such disclosure that the invention is capable of many further modifications without departing from the spirit and scope thereof, as set forth in the appended claims.

Having thus described my invention what I

claim as new and desire to secure by Letters Patent is:

1. A shoulder support for a hand telephone receiver-transmitter set comprising a flat plate of generally ovate form, a generally ovate opening formed in said plate, said opening passing completely through the plate and opening out through one edge thereof at one side of the longitudinal axis of said plate with the longitudinal axis of the opening disposed transversely to the longitudinal axis of the plate, said plate at the point where said opening breaks the continuity of the edge of the plate being provided with a pair of lugs extending partially across said opening to thereby restrict access to said opening, at least one of said lugs being movably mounted, and spring means urging said lug to a position restricting access to said opening, but being yieldable against said spring means to move 15 to a position to permit the entrance of a transmitter-receiver instrument into said opening.

2. The structure defined in claim 1 wherein said movably mounted lug is pivoted about an axis substantially perpendicular to the plate, said 25 lug being provided with a tail-piece, and said spring means is positioned to resiliently urge said tail-piece to a position in which the lug restricts access to said opening.

3. The structure defined in claim 1 wherein 30 said movably mounted lug is mounted for sliding movement to and from a position restricting access to said opening, and said spring means is positioned to urge said lug into its restricting position.

35 ALEXANDER G. HARRIS.
